UNITED STATES PATENT OFFICE.

HOWARD M. BARBER, OF STONINGTON, CONNECTICUT, ASSIGNOR, BY MESNE ASSIGNMENTS, TO C. B. COTTRELL & SONS COMPANY, OF NEW YORK, N. Y., A CORPORATION OF DELAWARE.

PRINTING-PRESS.

1,312,151.

Specification of Letters Patent.

Patented Aug. 5, 1919.

Application filed September 23, 1913. Serial No. 791,334.

To all whom it may concern:

Be it known that I, HOWARD M. BARBER, a citizen of the United States, and resident of Stonington, in the county of New London 5 and State of Connecticut, have invented a new and useful Improvement in Printing-Presses, of which the following is a specification.

The object of my invention is to provide 10 certain improvements in printing presses whereby two separate products may be delivered or a single product may be delivered.

A further object of my invention is to provide a printing press of the above character which comprises two printing mechanisms, each mechanism being arranged to print upon one or both sides of its particular web, or the two mechanisms may be utilized for printing two colors upon each side or 20 three colors on one side and one color on the opposite side of a single web.

I have discovered that it would be extremely desirable to provide a printing press in which one printing mechanism only need 25 be used for printing upon both sides of a web or for printing two colors upon one side only of a web where a single product is desired or the two printing mechanisms may be used for printing one color on each side 30 or for printing two colors on one side of each of two separate webs where a double product is desired, or for passing one web through both printing mechanisms so as to deliver a single product having two colors 35 printed upon each side or three colors printed upon one side and one color on the opposite side of the web. These results may be accomplished by my invention, a practical embodiment of which is represented in the 40 accompanying drawings in which,

Figure 1 represents the printing press in side elevation with the parts in the position which they assume when a single web is being printed with two colors upon each side 45 thereof.

Fig. 2 is a detail side view partly in section, with the gears removed which connect the two printing mechanisms and the parts in the positions which they assume when 50 two separate webs are being printed with one color on each side of each web.

Figs. 3, 4 and 5 are enlarged detail views showing more clearly one of the cylinder

adjusting devices, in the present instance, the device utilized for adjusting the impression cylinder of one of the couples of the upper printing mechanism. 55

Fig. 6 is a diagrammatic view showing the arrangement of the several parts when a single web is being passed through both 60 printing mechanisms for printing two colors upon each side of the web.

Fig. 7 is a diagrammatic view showing the arrangement of the several parts when a single web is being passed through both 65 printing mechanisms for printing three colors on one side and one color on the other side.

Fig. 8 is a diagrammatic view showing the arrangement of the parts when two 70 separate webs are being passed through the two printing mechanisms for printing a single color on each side of each web, and

Fig. 9 is a diagrammatic view showing the arrangement of the parts when two 75 separate webs are being passed through the two printing mechanisms for printing two colors on one side only of each web.

The printing press herein shown comprises upper and lower printing mechanisms each having two printing couples, the plate cylinders of the lower couple being denoted by 1 and 2 and their respective impression cylinders by 3 and 4. The plate cylinders of the upper printing mechanism are denoted by 5 and 6 and their respective impression cylinders by 7 and 8. Suitable inking mechanisms 9, 10, 11, 12, are provided for the plate cylinders 1, 2, 5, 6. The shafts 13, 14, 15, 16, of the cylinders 1, 2, 3, 4, are 80 provided with gears 17, 18, 19 and 20. The gears 17 and 19 are always in mesh and the gears 18 and 20 are always in mesh. The gear 20 is brought into and out of mesh 85 with the gear 19 and the gear 18 is brought into and out of mesh with the gear 19, by suitable adjusting means to be hereinafter described. 90

The shafts 21, 22, 23, 24 of the cylinders 5, 6, 7, 8, are provided with gears 25, 26, 100 27, 28. The gears 26 and 27 are at all times in mesh. The gear 25 is brought into and out of mesh with the gear 27 and the gear 28 is brought into and out of mesh with the gears 25 and 27 by suitable adjusting means 105 to be hereinafter described. Intermeshing

gears 29 and 30 are fixed on the shafts 15 and 23 of the cylinders 3 and 7, respectively.

Substantially similar adjusting devices are used for adjusting the plate cylinder 2 into and out of coaction with the impression cylinder 3; the impression cylinder 4 into and out of co-action with the plate cylinder 2; the plate cylinder 5 into and out of coaction with the impression cylinder 7; and the impression cylinder 8 into and out of coaction with the plate cylinder 5. I will therefore describe one only of these adjusting means, namely, the one applied to the shaft 24 of the impression cylinder 8, as this will give a clear understanding of the operation of all of the other adjusting devices.

The inner and outer bearings 31, 32, for the shaft 24 are mounted to slide in the boxes 33. Inner and outer adjusting screws 34, 35, are provided, which screws bear against the inner and outer bearings 31, 32. The outer screw 35 is provided with a worm gear 36 which meshes with a worm 37 on a shaft 38, which shaft is geared to a hand shaft 39 by gears 40, 41. This arrangement permits the adjustment of both ends of the shaft without losing its parallelism with the shafts of the other cylinders 30 of the printing mechanism.

In Fig. 6 I have shown the plate cylinder 2 of the lower printing mechanism adjusted into coaction with the impression cylinder 3. The impression cylinder 4 of the lower printing mechanism has been adjusted out of coaction with the plate cylinder 2. In the upper printing mechanism the plate cylinder 5 has been adjusted into coaction with the impression cylinder 7, and the impression cylinder 8 has been adjusted out of coaction with the plate cylinder 5. With the parts in this position, the one web is led through both printing mechanisms and two colors are printed upon one side of the web in the lower printing mechanism and two colors are printed on the other side of the web in the upper printing mechanism.

In Fig. 7, I have shown the plate cylinder 2 of the lower printing mechanism adjusted into coaction with the impression cylinder 3. The impression cylinder 4 of the lower printing mechanism has been adjusted out of coaction with the plate cylinder 2. In the upper printing mechanism the plate cylinder 5 has been adjusted out of coaction with the impression cylinder 7, and the impression cylinder 8 has been adjusted into coaction with the plate cylinder 5. With the parts in this position, the one web is led 60 through both printing mechanisms and three colors are printed upon one side of the web and one color is printed upon the other side of the web. In the present instance, two colors are printed upon one side of the 65 web in the lower printing mechanism and

one color upon each side of the web in the upper printing mechanism to accomplish the above stated result. It will also be noted that the web is led first between the plate cylinder 5 and impression cylinder 8 in the 70 upper printing mechanism.

In Fig. 8, I have shown the plate cylinder 2 as adjusted out of its coaction with the impression cylinder 3 and the impression cylinder 4 adjusted into coaction with the 75 plate cylinder 2. I have also shown the plate cylinder 5 adjusted out of coaction with the impression cylinder 7 and have shown the impression cylinder 8 as adjusted into coaction with the plate cylinder 5. 80 With the parts in this arrangement, two separate webs may be passed through the machine, one through each printing mechanism and having one color printed on each side thereof.

In Fig. 9, I have shown the plate cylinder 2 as adjusted into coaction with the impression cylinder 3, and I have shown the impression cylinder 4 as adjusted out of coaction with the plate cylinder 2. I have also 90 shown the plate cylinder 5 adjusted into coaction with the impression cylinder 7, and I have shown the impression cylinder 8 as adjusted out of coaction with the plate cylinder 5. With the parts in this arrangement, two separate webs may be passed through the machine, one through each printing mechanism and having two colors 95 printed upon one side only thereof.

It will also be noted that in the arrangements shown in Figs. 8 and 9, if a half product is only desired, then only one of the printing mechanisms need be used.

While I have shown several ways in which my invention can be utilized, it is 105 obvious that I do not wish to limit myself to these particular ways only but contemplate any way of utilizing the invention which can be obtained without a re-formation and reconstruction of the parts.

What I claim is:

1. A printing press consisting of only two multicolor printing mechanisms, each of which consists of only two printing couples, said printing mechanisms being operable to 115 print a plurality of colors on each side of one web or one color on each side of two separate webs without the use of turners.

2. A printing press consisting of only two multicolor printing mechanisms, each of which consists of only two printing couples, said printing mechanisms being operable to print a plurality of colors on each side of one web or a plurality of colors on one side and one color on the other side of one web 125 without the use of turners.

3. A printing press consisting of only two two-color printing mechanisms, each of which consists of only two printing couples, said printing mechanisms being operable to 130

print two colors on each side of one web or one color on each side of two separate webs without the use of turners.

4. A printing press consisting of only two two-color printing mechanisms, each of which consists of only two printing couples, said printing mechanisms being operable to print two colors on each side of one web or three colors upon one side and one color on the other side of one web without the use of turners.

5. A printing press consisting of only two multicolor printing mechanisms, each of which consists of only two printing couples, said printing mechanisms being operable to print a plurality of colors on each side of one web or a plurality of colors upon one side and one color on the other side of one web or one color on each side of two separate webs without the use of turners.

6. A printing press consisting of only two two-color printing mechanisms, each of which consists of only two printing couples, said printing mechanisms being operable to print two colors on each side of one web or three colors on one side and one color on the other side of one web or one color on each side of two separate webs without the use of turners.

7. A printing press consisting of only two multicolor printing mechanisms, each of which consists of only two printing couples, said printing mechanisms being operable to print a plurality of colors on each side of one web or a plurality of colors on one side and one color on the other side of one web or a plurality of colors on one side only of each of two separate webs without the use of turners.

8. A printing press consisting of only two two-color printing mechanisms, each of which consists of only two printing couples,

said printing mechanisms being operable to print two colors on each side of one web or three colors upon one side and one color upon the other side of one web or two colors on one side only of each of two separate webs without the use of turners.

9. In a printing press, a printing mechanism comprising two printing couples and means for moving the plate cylinder of one couple into and out of coaction with the impression cylinder of the other couple.

10. In a printing press, two printing mechanisms each comprising two printing couples and means for moving the plate cylinder of one couple into and out of coaction with the impression cylinder of the other couple.

11. In a printing press, a printing mechanism comprising two printing couples and means for moving the plate cylinder of one couple into and out of coaction with the impression cylinder of the other couple and for moving the impression cylinder of the first named couple into and out of coaction with its plate cylinder.

12. In a printing press, two printing mechanisms each comprising two printing couples and means for moving the plate cylinder of one couple of each mechanism into and out of coaction with the impression cylinder of the other couple and for moving the impression cylinder of each of the first named couples into and out of coaction with its plate cylinder.

In testimony, that I claim the foregoing as my invention, I have signed my name in presence of two witnesses, this nineteenth day of September A. D. 1913.

HOWARD M. BARBER.
